(57) **CLAIM**

The ornamental design for a flashlight as shown and described.

DESCRIPTION

FIG. 1 is a front, top, and right side perspective view of a flashlight, showing our new design;

FIG. 2 is a front, top, and left side perspective view thereof;

FIG. 3 is a front, bottom, and right side perspective view thereof;

FIG. 4 is a rear, top, and right side perspective view thereof;

FIG. 5 is a right side view thereof;

FIG. 6 is a left side view thereof;

FIG. 7 is a top view thereof;

FIG. 8 is a bottom view thereof;

FIG. 9 is a front view thereof; and

FIG. 10 is a rear view thereof.

The broken lines in the drawings depict portions of the flashlight that form no part of the claimed design.
